US0D1009696S

(12) **United States Design Patent** (10) **Patent No.:** **US D1,009,696 S**
(45) **Date of Patent:** **** Jan. 2, 2024**

(54) **AIRCRAFT**

(71) Applicant: **Aurora Flight Sciences Corporation, a subsidiary of The Boeing Company, Manassas, VA (US)**

(72) Inventors: **Tony Shuo Tao**, Somerville, MA (US); **William Cooper Thalheimer**, Cambridge, MA (US); **Robert William Parks**, San Jose, CA (US); **Adrian Hachen**, Bern (CH); **Bruno Miguel Costa Moniz**, Thalwill (CH)

(73) Assignee: **Aurora Flight Sciences Corporation, a subsidiary of The Boeing Company, Manassas, VA (US)**

(**) Term: **15 Years**

(21) Appl. No.: **29/724,709**

(22) Filed: **Feb. 18, 2020**

(51) LOC (14) Cl. **12-07**

(52) U.S. Cl.

USPC **D12/326**

(57) **CLAIM**

The ornamental design for an aircraft, as shown and described.

DESCRIPTION

FIG. 1 is a top, front, right isometric view of an aircraft showing the new design;

FIG. 2 is a bottom, rear, left isometric view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a top, front, right isometric view shown in an alternative configuration of use with the forward rotors pivoted to a forward-thrust position.

The broken lines shown in the drawings illustrate portions of the aircraft that form no part of the claimed design.

1 Claim, 9 Drawing Sheets
